US00D916491S

(12) **United States Design Patent** (10) **Patent No.:** **US D916,491 S**
Chen (45) **Date of Patent:** **** Apr. 20, 2021**

(54) **PAPER HOLDER**

(71) Applicant: **SHENZHEN DAIWEI TECHNOLOGY CO., LTD**, Shenzhen (CN)

(72) Inventor: **Shaobo Chen**, Shenzhen (CN)

(73) Assignee: **SHENZHEN DAIWEI TECHNOLOGY CO., LTD**, Shenzhen (CN)

(**) Term: **15 Years**

(21) Appl. No.: **29/751,302**

(22) Filed: **Sep. 21, 2020**

(51) LOC (13) Cl. **06-04**

(52) U.S. Cl.

USPC **D6/522**

(58) **Field of Classification Search**

USPC D6/522, 523, 515-521, 524; D8/349, D8/354, 363, 373, 394; 206/77.1, 13.1, 206/86.01, 87.01; 221/14, 92, 105, 146.1, 221/146.2, 649; 222/281-282

Primary Examiner — Nathan M Johnston

(57) **CLAIM**

The ornamental design for a paper holder, as shown and described.

DESCRIPTION

FIG. 1 is a perspective view of a paper holder showing my new design;

FIG. 2 is another perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

1 Claim, 8 Drawing Sheets
